Patented Oct. 29, 1974

233,399

COOKING GRILL

Edward M. Marshall, 4819 Hidden Harbor Blvd. SW,
Fort Myers, Fla. 33901

Filed May 21, 1973, Ser. No. 362,375

Term of patent 14 years

Int. Cl. D7—02

U.S. Cl. D7—110

FIG. 1

FIG. 2

FIG. 3

FIG. 4

FIG. 5

FIG. 6

FIG. 1 is a front elevation of a cooking grill showing my new design.

FIG. 2 is a top plan view thereof.

FIG. 3 is an end elevation thereof.

FIG. 4 is a rear elevation thereof.

FIG. 5 is a bottom plan view thereof.

FIG. 6 is a side elevation thereof, opposite that shown in FIG. 3.

I claim:

The ornamental design for a cooking grill, as shown.
